UNITED STATES PATENT OFFICE.

SAMUEL S. MARCUS AND SAMUEL KRAKAUER, OF NEW YORK, N. Y.

COVERED SPRING STRUCTURE.

Application filed August 16, 1922. Serial No. 582,228.

To all whom it may concern:

Be it known that we, SAMUEL S. MARCUS and SAMUEL KRAKAUER, citizens of the United States, and residents of the city of 5 New York, borough of the Bronx, in the county of Bronx and State of New York, have invented a new and Improved Covered Spring Structure, of which the following is a full, clear, and exact description.

10 This invention has relation to covered spring structures and has particular reference to cushion seat or bed spring structures which include a plurality of coiled springs placed side by side to form a resilient element.

As an object the invention contemplates in a covered spring structure, means for maintaining the individual spring elements under compression, said means also serving 20 to insulate the convolutions of said elements from each other to prevent clashing or knocking of the same against the convolutions of contiguous elements.

As a further object the invention contemplates means for holding the spring elements under compression which also serves as means for holding the individual spring elements in contiguous relation and for eliminating the release of the same from 30 their initial or normal compression in event of the breakage or displacement of the holding clips.

As a further object the invention contemplates a simple and effective means for associating the individual elements of a spring seat structure, which means renders the manufacture and production inexpensive as well as strong and durable.

With the above recited and other objects 40 in view, the invention resides in the novel construction set forth in the following specification, particularly pointed out in the appended claims and illustrated in the accompanying drawings, it being understood that 45 the right is reserved to embodiments other than those actually illustrated herein to the full extent indicated by the general meaning of the terms in which the claims are expressed.

50 In the drawings—

Figure 1 is a fragmentary plan view of a spring structure embodying the invention.

Fig. 2 is a sectional view therethrough taken approximately on the line 2—2 of 55 Fig. 1.

Fig. 3 is a transverse fragmentary sec-

tional view taken approximately on the line 3—3 of Fig. 1.

Referring to the drawings by characters of reference, 10 designates a plurality of 60 coiled contractile spring sections which are arranged contiguous to each other to make up a spring structure to be employed as a bed spring, or cushion seat structure. It has been definitely established that cushion 65 springs when kept under compression are superior in action to those that are not so kept, and the invention therefore relates to the means for connecting the springs 10 to each other and the manner in which the same are held under an initial or normal compression. As illustrated a strip of flexible material 11 is connected at one extremity by means of a clip 12 to the upper end convolution of one of the springs 10 and 70 is then passed downwardly toward the opposite end and under the same where it is secured at diametrically opposite points by the clips 12 to the lower end convolution of 75 said spring 10. The strip is then alternately 80 threaded upwardly and over the upper end convolutions and downwardly and under the lower end convolutions of the adjacent springs 10 in a substantially sinuous path. At each point of change of direction of the 85 strip, the same is secured by one of the clips 12 to the spring convolution with which it engages. The contiguous convolutions of adjacent springs 10 are retained in juxtaposition by means of the clip 12 which attaches 90 the strip to the spring. In the next adjacent row of springs, the strip is alternately threaded over and under the spring sections in a substantially sinuous course or path as illustrated, and in attaching the contiguous upper and lower convolutions of the 95 spring sections of adjacent rows a strip 13 is connected at its upper and lower ends respectively to the convolutions of the spring sections of the adjacent rows by means of 100 the clips 12 which attach the rows together. This construction interposes what may be termed an insulating strip between the convolutions to prevent clashing or interference of the intermediate convolutions with 105 each other when weight is brought to bear on the structure. The sinuous arrangement of the strips 11 interposes between the contiguous spring sections 10 of each row an insulating portion for a like purpose and 110 said sinuous threading of the strip serves to hold the springs under the initial or nor-

mal compression even though one or more of the clips 12 should be broken or detached.

We claim:

1. In combination, a covered spring structure embodying a plurality of rows of contiguous spring sections, and a common means for holding the same under partial compression and for insulating the convolutions thereof from each other, comprising a strip of flexible material connected at one extremity to one of the end convolutions of an end spring section and passed alternately under and over the spring sections of each row, and means for securing the strips at diametrically opposite points to the end convolutions.
2. In combination, a covered spring structure embodying a plurality of rows of contiguous spring sections, and a common means for holding the same under partial compression and for insulating the convolutions thereof from each other, comprising a strip of flexible material connected at one extremity to one of the end convolutions of an end spring section and passed alternately under and over the spring sections of each row, and means for securing the strips at diametrically opposite points to the end convolutions, said means of securement serving to also connect the spring sections in contiguous relation.
3. In combination, a covered spring structure embodying a plurality of rows of contiguous spring sections and a common means for holding the same under partial compression and for insulating the convolutions thereof from each other, comprising a strip

of flexible material connected at its opposite ends respectively to an end convolution of the end spring and alternately passed under and over the intermediate spring sections of each row, and means for securing the intermediate portions of the strip to the end convolutions respectively at its points of contact therewith.

4. In combination, a covered spring structure embodying a plurality of rows of contiguous spring sections and a common means for holding the same under partial compression and for insulating the convolutions thereof from each other, comprising a strip of flexible material connected at its opposite ends respectively to an end convolution of the end spring and alternately passed under and over the intermediate spring sections of each row, means for securing the intermediate portions of the strip to the end convolutions respectively at its points of contact therewith, and means for connecting the contiguous points of the end convolutions of the spring sections of the adjacent rows and for insulating the convolutions thereof comprising a single vertical strip of a length approximately equal to the height of a spring section and passing between adjacent spring sections, the upper end of said strip being connected to adjacent parts of the contiguous upper convolutions and the lower end being connected to adjacent parts of the lower contiguous convolutions.

SAMUEL S. MARCUS.
SAMUEL KRAKAUER.
